JEWEL

Herman Bogoff, Chicago, Ill.

Application October 28, 1950, Serial No. 12,761

Term of patent 14 years

(Cl. D45—2)

To all whom it may concern:

Be it known that I, Herman Bogoff, a citizen of the United States, residing at Chicago, in the county of Cook and State of Illinois, have invented a new, original, and ornamental Design for a Jewel, of which the following is a specification, reference being had to the accompanying drawing, forming part thereof, wherein—

Fig. 2 is an enlarged top plan view of the jewel;

Fig. 3 is a side elevation thereof, taken along line 3—3 of Fig. 2; and

Fig. 4 is a transverse section therethrough, taken on line 4—4 of Fig. 2.

I claim:

The ornamental design for a jewel, substantially as shown.

HERMAN BOGOFF.
